UNITED STATES PATENT OFFICE.

GUSTAV NICHOLSON, OF ITACUBURI DEL ROSARIO, PARAGUAY.

FIREARM.

Application filed April 30, 1924. Serial No. 710,058.

To all whom it may concern:

Be it known that I, GUSTAV NICHOLSON, a citizen of Paraguay, residing at Itacuburi del Rosario, Republic of Paraguay, have invented certain new and useful Improvements in Firearms; and I do hereby declare the following to be a full, clear, and exact description of the invention, such as will enable others skilled in the art to which it appertains to make and use the same.

This invention relates to new and useful improvements in fire-arms, and particularly to revolvers.

The principal object of the invention is to provide a firing mechanism for a revolver wherein the ordinary pivoted, and hook-shaped hammer is done away with, and the danger of such hammer catching in the clothing of the user, obviated.

Another object is to provide a mechanism whereby the hammer is automatically cocked and released by the single rearward pivotal movement of the trigger.

A further object is to provide a mechanism of this character wherein the hammer travels in a straight line, and is adapted to be cocked by hand.

Other objects and advantages will be apparent from the following description when taken in connection with the accompanying drawing.

In the drawing:

Figure 1 is a vertical longitudinal sectional view through a fire-arm made in accordance with the invention, and showing the mechanism in normal position.

Figure 2 is a similar sectional view showing the mechanism in the position assumed when the hammer is cocked and on the point of being released.

Figure 3 is a similar sectional view showing the position of the parts when the hammer has been cocked by hand.

Figure 4 is a vertical sectional view on the line 4-4 of Figure 3.

Referring particularly to the accompanying drawing, 10 represents the frame of the grip of the stock of the revolver, which has the removable side plates 11, retained in position by the screw 12. The upper portion of the stock is formed with the longitudinal grooves 13, in which is slidably disposed the hollow hammer 14, the rear end of the said hammer being slidable through an opening 15, in the rear end of the upper portion of the stock, where it is provided with a milled

knob 16. Rigidly mounted transversely in the stock, between the grooves 13, and disposed through the longitudinal slots 17 of the hammer, is a web or bar 18, a coil spring 60 being disposed within the hammer and bearing against the forward end wall and against the said bar, as shown at 19. On the forward end wall of the hammer there is formed the integral firing pin 20, which passes through an opening 21, in the breech 22, to strike the cap of the cartridge 23. Between the rear end wall of the hammer, and the rear side of the bar 18, is a shorter coil spring 24, which serves to take up the 70 recoil of the hammer.

The fire-arm is also provided with the revolving cartridge cylinder 25, and below the cylinder is the trigger guard 26. Pivotedly supported within the guard 26 is the trigger 27, the same having a rearward extension 28, projecting through an opening in the grip frame, and provided with a lateral pin 29, engaged in the slot 30' in the adjacent end of the arm 30. This arm 30 is pivotally 80 mounted in the frame, at the rear side thereof. On the extension 28 of the trigger there is pivotally mounted an upwardly extending pawl 31, which engages with the ratchet 32 of the cylinder, for the purpose of rotating the same. Pivotedly connected to the forward end portion of the arm 30, and extending vertically therefrom, is a link 33.

To the upper end of the link 33 there is pivoted the safety actuating arm 34, and pivoted to the inner end of the arm 34, inwardly of the link 33, is the cocking arm 35. The arm 35 has a projection 36, on its free end which engages in a notch 37, formed in the lower side of the hammer. The arm 34 has an angularly extending end portion 38 which is swiveled in the safety sliding block 40, and is pivotally mounted within the stock. Connected to and extending between the arm 30, and the arm 35, is a coil spring 41, which exerts pressure to force the arms 30 and 35 apart. On the arm 35, adjacent the end of the spring 41, is a roller 35' which is adapted to bear against the lower side of the hammer, as the hammer moves forwardly and rearwardly.

When the trigger is pulled rearwardly, the pin 29 slides in the slot 30', and while at the same time the arm 30 is raised to turn the cylinder a single notch, and thereby present a new cartridge in the breech. The arm 30 is elevated by the pin 29, and as the

arm 30 moves upwardly to a greater extent, it carries the arms 34 and 35 upwardly, the latter assuming a position approximately horizontally beneath the lower side of the hammer, but out of contact therewith, except for the roller 35', while the arm 34 slides the block 40 downwardly from in front of the hammer. The full rearward movement of the trigger causes the arm 35 to assume a position wherein the projection 36 will be withdrawn from the notch 37 of the hammer, so that the hammer will be released and projected forwardly, by the spring 19, to strike its pin 20 against the cartridge. The recoil of the hammer is taken up by the shorter spring 24. Thus, the cocking and discharging of the fire-arm is accomplished by the single movement of the trigger.

Pivoted on the forward side of the frame 10 is an upwardly extending lever 42, the upper end of which is slightly curved, as at 43, and provided with a terminal shoulder 44, for the reception of one end wall of the slot 44' formed through the lever 30, and through which the arm 42 is arranged to move as the lever 30 rises and falls. The pivotal portion of the lever 42 is formed with a downward projection 45, and between this projection and the adjacent portion of the frame 10, is a coil spring 46, which serves to normally urge the upper end of the lever toward the said pivotal connection. By this construction the hammer may be pulled, or cocked, by hand, the operator grasping the knob 16, and pulling the hammer rearwardly through the opening 15. The movement of the hammer, above-mentioned, causes the wall of the notch 37 to engage with the projection 36, and draw the members 33, 34, and 35, upwardly, the spring 41 assisting in such movement of the arm 35. When the lever 30 has moved upwardly to the proper distance, the pivotal connection before-mentioned, between the arms 34 and 35, will permit the arm 42 to be rocked rearwardly by its spring 46, so that the upper end thereof will be disposed beneath the lever 30 with the wall of the slot 44' resting on the shoulder 44. The hammer will thus be held cocked, and to fire the revolver, it is only necessary to pull the trigger rearwardly the remaining short distance to move the arm 35 upwardly and release the projection 36 from the notch 37, when the hammer will fly forwardly. Release of the trigger permits the arm 42 to be rocked back to normal position by its spring 46. As the parts move toward normal position, after the firing, and release of the trigger, the lug 49, on the forward pivoted end of the arm 34, will engage the shoulder 14', at the forward end of the

hammer, to move the hammer rearwardly a sufficient distance to permit the block to slide into safety position between the hammer and the breech wall.

Pivoted beneath the cylinder 25 is a spring pressed block 50 having a notch 51 receiving the lug 52 of the trigger, and the lug 53 for engagement in the notches of the cylinder, shown at 54. This constitutes the cylinder lock.

What is claimed is:

1. A revolver mechanism including a slideable spring pressed hammer, a slideable block in advance of the hammer, a trigger, an arm movable by the trigger, an arm operatively engaged with the hammer for cocking and releasing the hammer, an arm operatively connected with the slideable block for moving the block out of the path of the hammer, and operative connections between the first-named arm and the second-named arms for actuating the latter upon movement of the trigger.

2. A revolver mechanism including a slideable spring pressed hammer, a trigger, a pivoted arm movable by the trigger, an arm pivotally connected with the movable arm, a second arm pivotally connected with said movable arm, hammer engaging and releasing means on the first of the arms, and a safety means operable by the second pivotal arm.

3. A revolver mechanism including a slideable spring pressed hammer, a slideable block in advance of the hammer, a pivoted trigger, a pivoted arm operatively engaged by the trigger and having an opening, a vertical link movably carried by the pivoted arm, an arm pivotally carried by the upper end of the link, a second arm pivotally carried by the first arm, a guide for the hammer, a projection on the second-named arm, the hammer having a notch receiving the said projection, and a means movable by the link carried arm and engageable with the first-named pivoted arm.

4. A revolver mechanism including a slideable spring pressed hammer, a slideable block in advance of the hammer and having an opening therein, a pivoted trigger, a pivoted arm having one end engaged with the trigger for movement thereby, a link carried by the pivoted arm, and a toggle connected with the link and having engagement with the hammer, and having a projection engaged in the opening of said slideable block.

In testimony whereof, I affix my signature, in the presence of two witnesses.
